DIRECTIVE ANTENNA SYSTEM

Nils E. Lindenblad, Rocky Point, N. Y., assignor
to Radio Corporation of America, a corpora-
tion of Delaware

Application December 31, 1940, Serial No. 372,609

9 Claims. (Cl. 250—11)

The present invention relates to an antenna system for ultra-high frequency radiation and, more particularly, to antenna systems employing parabolic reflectors for projection of the radiation in a desired direction.

It has previously been attempted to conserve the direct forward radiation from a radiator at the focus of a parabolic reflector by means of a spherical cap over the radiator. This method yields an improvement in directivity but also results in an increase in the resonance characteristic or the Q of the radiation system. This is very seldom desirable in modern wide band frequency modulated communication circuits.

An object, therefore, of the present invention is to improve the directivity of the parabolic reflectors for the projection of ultra high frequency radiation.

A further object of the present invention is the improvement of the directivity of a parabolic reflector for ultra high frequency radiation without at the same time increasing the resonance characteristic of the system.

In accordance with my invention I propose to increase the directivity of a radiator at the focus of a parabolic reflector by placing a flat disc of the order of a wavelength in diameter or less at a distance less than a half wavelength in front of the radiator.

According to another aspect of my invention, I also propose to improve the field distribution across the reflector by placing a conductive cone between the radiator within the reflector and the portion of the reflector immediately back of the radiator.

My invention will be more fully understood by reference to the following detailed description which is accompanied by a drawing in which reference character 1 indicates a parabolic reflector having mounted therein at the focus a radiating antenna structure 2. A portion of the reflector 1 is shown broken away in order that the interior arrangement may be clearly seen. The antenna structure 2 is connected to energizing or signal transducer means (not shown) by a transmission line TL. Immediately in front of the radiator 2 is placed a conductive disc or shading element 3 which preferably has a diameter of the order of one wavelength and is placed a distance of a half the operating wavelength or less in front of radiator 2. The distance between the radiator 2 and the conductive disc 3 is not critical but in general it will be somewhat less than a half of the operating wavelength. The presence of the disc-like shading element 3 pre-

vents the direct radiation of energy from radiator 2 and thus improves the radiation pattern of the antenna system in the same way as do the spherical caps previously known in the art.

5 However, the flat conductive disc 3 does not change the resonance condition of the radiator to nearly the same extent as the spherical caps due to sectional variation of distance to radiator.

In a reflector of practical parameter, the distance from the radiator 2 to the reflecting surface of the reflector 1 increases considerably towards the edge of the reflector. I have discovered that this condition results in a poor field distribution across the face of the reflector so

10 that all the gain that is theoretically possible to obtain with a certain reflector area is not obtained. I find that it is possible to correct this condition by the use of a centrally located cone 5, as indicated in the accompanying drawing.

15 A portion of reflector 1 has been shown as broken away in order to more clearly disclose cone 5. The presence of this cone does not materially affect the resonance condition of the radiator. As indicated in the drawing, the included angle

20 of the cone 5 should preferably be of the order of 90° and the length of the side should be of the order of a half wavelength, though this is not critical.

25 The theoretical formula for the gain of a reflector having an opening area A expressed in terms of the wavelength squared and when using uniform power distribution is $\text{Gain} = K \times A$ where K is equal to 7.8. Those skilled in the art have heretofore found that it is difficult to exceed 30 practically a value of 4 for the constant K as compared to the theoretical value of 7.8.

35 By utilizing the flat conductive disc 3 and the centrally located cone 5 in accordance with the teachings of my invention, it is possible to obtain 40 a value for K of 5.6, or more, which represents a conservative interpretation of actual measurements on a physical embodiment of my invention. It will be seen that this is a substantial improvement over what has previously been obtainable.

45 My invention has been described in detail with reference to a reflector in the form of a paraboloid of revolution and a conical angle limiting structure but it should be clearly understood that 50 the same principles may be used with a reflector having the form of a cylindrical parabola and a prismatic angle limiting structure.

55 While I have particularly shown and described several modifications of my invention, it is to be distinctly understood that my invention is not

limited thereto but that improvements within the scope of the invention may be made.

I claim:

1. An antenna system comprising radiating means within a parabolic reflector, a flat shading element disposed across the opening of said reflector in front of said radiating means at a distance less than half the operating wavelength therefrom and means interposed between said reflector and said radiating means for re-distributing the field within said reflector for most effective use of the surface of said reflector.

2. An antenna system comprising radiating means within a parabolic reflector, a flat shading element disposed across the opening of said reflector in front of said radiator means at a distance less than half the operating wavelength therefrom and means interposed between said reflector and said radiating means for limiting the effective surface of said reflector, said last means comprising a right circular cone.

3. An antenna system comprising radiating means within a parabolic reflector, a flat shading disc disposed across the opening of said reflector in front of said radiator means at a distance less than half the operating wavelength therefrom and means interposed between said reflector and said radiating means for limiting the effective surface of said reflector, said last means comprising a right circular cone having a side equal in length to a half of the operating wavelength.

4. An antenna system comprising radiating means within a parabolic reflector, a flat shading disc disposed across the opening of said reflector in front of said radiator means at a distance less than half the operating wavelength therefrom and means interposed between said reflector and said radiating means for re-distributing the field within said reflector for most effective use of the surface of said reflector, said last means comprising a right circular cone having a side equal in length to a half of the operating wavelength.

5. An antenna system comprising radiating means within a parabolic reflector and means interposed between said reflector and said radiating means for distributing the field within said reflector for a most effective use of the surface

of said reflector, said means comprising a conductive cone, the apex of said cone facing said radiating means, said cone having a side length of the order of one-half of the operating wavelength of said system.

6. An antenna system comprising electromagnetic radiating means within a parabolic reflector and means interposed between said radiating means and a portion of said reflector for limiting the distribution of radiated energy to predetermined portions of said reflector, said means comprising a conductive body tapering from said reflector toward said radiating means, the length of the tapering side of said body being of the order of one-half of the operating wavelength of said system.

7. The combination with a radio frequency radiator and wave directive structure for concentrating radiation from said radiator in a given direction of means interposed between said radiator and a portion of said structure for limiting distribution of radiated energy from said radiator to predetermined portions of said structure, said means including a conductive body tapering from said structure toward said radiator the length of said conductive body being of the order of one-half of the operating wavelength of said radiator.

8. An antenna system comprising radiator means within a parabolic reflector and means interposed between said reflector and said radiator means for distributing the field within said reflector for a most effective use of the surface of said reflector, said means comprising a right circular conductive cone, the apex of said cone facing said radiator means, said cone having a side length of the order of one-half of the operating wavelength of said system.

9. An antenna system including radiating means within a parabolic reflector, a flat shading element disposed across the opening of said reflector in front of said radiating means, and means interposed between said reflector and said radiating means for re-distributing the field within said reflector for the most effective use of the surface of said reflector, said last-mentioned means including a conductive cone, the apex of said cone facing said radiating means.
